UNITED STATES PATENT OFFICE.

CHARLES E. H. ARMBRUSTER, OF DENVER, COLORADO.

CASING FOR PRODUCING AN AIR-TIGHT CHAMBER OVER OR AROUND A PORTION OF THE HUMAN BODY.

1,172,662.

Specification of Letters Patent.

Patented Feb. 22, 1916.

Application filed September 2, 1914. Serial No. 859,910.

To all whom it may concern:

Be it known that I, CHARLES E. H. ARM-
BRUSTER, a citizen of the United States, re-
siding at Denver, in the county of Denver
5 and State of Colorado, have invented certain
new and useful Improvements in Casings
for Producing an Air-Tight Chamber Over
or Around a Portion of the Human Body,
of which the following is a specification.

10 My invention relates to the construction
of casings of the type used to produce an air
tight chamber over or around a portion of
the human body, in the method of treating
disease by vacuum and air-pressure, and its
15 primary object resides in providing a cas-
ing which may be readily applied to a hu-
man body to incase the portion to be treated
and which around its one or more openings
through which adjoining parts of the body
20 extend, has novel means for effecting an air
tight closure of the spaces between the edges
of said openings and the surface of the
parts extending therethrough.

25 The casings shown in the drawings and
hereinafter to be described, are more par-
ticularly adapted for use in the system of co-
operative devices for therapeutic treatment
disclosed in my application for patent, Num-
30 ber 859,908, filed synchronously with the
present application.

35 In the drawings in the various views of
which like parts are similarly designated,
Figure 1 represents a plan view of my im-
proved casing in the form which adapts it
for use to incase the thorax of a human
40 body, Fig. 2, a side elevation of the same,
Fig. 3, an elevation of a casing designed to
be applied to a limb of the body, Fig. 4, an
elevation of a casing adapted to inclose the
head, Fig. 5, a transverse section along the
45 line 5—5, Fig. 1, Fig. 6, a plan view of the
casing shown in Fig. 1, drawn to a reduced
scale, in connection with a flexible garment
adapted to incase the legs of a body to whose
50 thorax the casing is applied, Fig. 7, a per-
spective view of the flanged elastic member
which forms part of the closing means ap-
plied to the openings of the casing, Fig. 8,
a section taken along the line 8—8, Fig. 7,
55 Fig. 9, an outside elevation of one of the
closing means above referred to, detached

from the casing, Fig. 10, a reverse view of
the same, and Fig. 11, an enlarged section
through the closing means in connection
with the casing, the section through the 55
means having been taken on a line 11—11,
Fig. 9.

Referring more specifically to the draw-
ings, the reference numeral 2 designates a
casing composed of two complementary 60
halves 3 and 4 which in the plane of their
juncture are provided with outwardly ex-
tending flanges 5 and 6. The two parts are
made of metal of sufficient rigidity to over-
come the tendency to collapse, produced by 65
a vacuum within the casing or to prevent
distortion when air of more than atmos-
pheric pressure is introduced into the same.
The flanges on one of the halves have headed
70 studs 7 which project through correspond-
ing apertures in the flanges of the other half,
and the latter are provided with hasps 8
which by engagement with the headed ends
of the studs, firmly clamp the two halves of
75 the casing in air-tight connection.

The casing illustrated in Figs. 1, 2 and 5
is particularly designed to incase the thorax
of the body. It has to this end four open-
ings which are proportioned and relatively
positioned to receive the neck, the arms and 80
the part of the body below the thorax, and
it has adjustable appliances to effect air
tight closures of the spaces between the re-
spective edges of its openings and the sur-
face of the body parts extending there-
85 through.

The above mentioned closing appliances
include a holding element composed of two
complementary sections 9 which are at-
tached to the halves of the casing to con-
jointly encircle its openings. The two sec-
tions of the element, which are identical in
construction, are each composed of an ar-
cuate, flat body-member 10 which along its
outer edge has an outwardly projecting rim
12. A second member 13 of similar form,
engages the outer surface of the first-men-
tioned member within its rim, and it is
likewise provided along its outer edge with
an outwardly projecting rim 14 which when
the two parts are assembled, extends flush
100 with the rim of the other part. The two

sections are secured in their co-operative relation, around the openings of the casing by means of screws 15 which extend through counter-sunk openings in the rims of the 5 body-members 10, into threaded apertures of flanges 16 which are formed on the casing around the openings, as is best shown in Fig. 11 of the drawings.

The member 10 of each section carries 10 upon its rim a pair of clamping devices which by engagement with the rim of the removable member 13, securely fasten the latter in its proper position with relation to the body member.

15 The clamping devices are preferably composed of leaf springs 17 which at one of their ends are pivoted on the rim of the member 10 as at 18, and which at their outer extremities are provided with knobs 20 to engage the rim of the plate 13.

25 The springs have at their outer ends, inwardly extending projections 20, which serve as stops to prevent outward movement of the member 13 when the springs are disengaged from its rim, for the purpose of adjusting the flexible body-engaging member hereinafter to be described.

30 The members of the closing appliance which by contact with the parts of the body extending through the openings of the casing, effect an air-tight closure of the spaces around said parts, consist of sleeves composed of wide bands 33 of ribbon or other resilient and elastic material provided with 35 integral longitudinal flanges 29 which extend at right angles to the outer surface of the sleeve intermediate of its ends.

40 At the line of junction of the flanges 29 with the respective bands, air-spaces 34 are formed which in the operation, serve to facilitate the adjustment of the sleeves to conform with the contour of the parts they encircle.

45 The central portions of the bands are made concave as indicated at 46 in Fig. 7 of the drawings, for engagement with the parts of the body around which they are applied.

50 The bands are fastened in their operative positions on the sections of the closing appliances by clamping their flanges between the members 10 and 13 of the same and they are secured against displacement by means of stud-bolts 30 which project from the body members of the sections through apertures 38 in their respective flanges, washers 31 which are placed on the bolts to engage the outer surfaces of the flanges and nuts 32 which are screwed on the bolts to drive 60 the washers against said surfaces.

65 The removable members 13 of the sections are provided with recesses 42 to clear the above-described fastening appliances when in their proper position with relation to the respective body members, and they

are secured against displacement by means of dowel pins on the body members which are fitted in corresponding openings in the inner members, as shown at 28 in Fig. 9. When the elastic members of the closing-appliances are thus secured on the respective sections of the holding element of the same, the concave middle portions of the bands extend in substantially concentric relation to the inner edges of the arcuate members 70 of the sections, while their end-portions project outwardly beyond the outer edges of the sections, to provide hand holds for the adjustment of the flexible members in the operation of the invention, which will hereinafter be described. The rims of the body-members of the sections have to this end been provided at their outer ends with slots 49, through which the flanges of the flexible members loosely extend. The portions of 80 the bands at opposite sides of their respective flanges project beyond the sides of the sections to which they are secured and when the sections are secured in their co-operative relation around an opening of the casing as 85 hereinbefore explained, the concave middle portions of the bands provide conjointly a flexible sleeve which encircles the part of the body extending through said opening. For the adjustment of the flexible sleeve 90 thus formed to tightly engage a part of the body extending through the same, the sections to which the parts of which said sleeve is composed, are provided at their adjoining ends, with inwardly sliding longitudinally aligned push bars 21 of L-shaped section which are mounted in pairs on both 100 members of each section to engage the arcuate portions 46 of the bands at opposite sides of their respective flanges. The bars are mounted on the members 10 and 13 by means of screws 23 which project through longitudinal slots in one of their sides which lie flat against the faces of the members with which the bars are associated.

110 The bars are provided at their inner ends with heads 24, the inner faces of which are curved to engage the arcuate portions of the bands at opposite sides of their flanges, and the bars on one of the members of each section are provided at their outer ends with pins 27 which project through openings in the ends of the corresponding bars on the other members of the sections, for the purpose of compelling the pairs of bars of opposite ends of the sections, to slide in synchronism.

115 To limit displacement of the bands composing the body encircling flexible sleeves of the closing appliances, by lateral deflection of their respective flanges, I have provided curved shutter blades 22 which at one of their ends are pivotally attached to the heads 24 of the push bars as at 25 and which are pressed gently toward the outer surfaces of 120

130

the curved portions 46 of the bands, by means of springs 26.

The blades 22 on the bars of each member of the sections, overlap at their outer ends, 5 and extend exteriorly of the curved portions of the respective bands in substantially parallel relation to the flanges of the same.

From the above description, it will be seen that the closing appliances around the several openings of the casing, consist each of a holding element composed of two complementary sections which hold in coöperative relation to each other the bands which conjointly provide the elastic sleeves to encircle the parts of the body extending through the said openings, and which carry means for the adjustment of said sleeves to conform with the contour of the body parts to effect an airtight closure around the same.

20 When the casing has been placed around the portion of the body to be treated and the halves of which it is composed, are clamped together, the operator adjusts the elastic sleeves around the parts of the body which 25 extend through the openings of the casing, in the following manner: The movable clamping members 13 of the sections of the closing appliance, are first of all, loosened by outward movement of the springs 17 to dis- 30 engage the rims of the members. When the springs are adjusted so that their knobs 19 engage the rims of the body members of the sections, the projections 23 of the same extend over the rims of the respective members 35 13 and thereby limit their displacement with respect to the body-members. The operator now grasps the ends of the flexible members which project beyond the outer ends of the push bars, and by drawing said ends simultaneously outwardly, compels the curved 40 portions of the bands to engage the part of the body, extending through the sleeve of which they form part. The flexible members are subsequently secured in their said ad- 45 justed positions by clamping their flanges between the members of the respective sections by readjustment of the springs 17, after which the closure of the space around the part of the body is completed by moving the 50 push-bars inwardly until the curved portions of the bands conform with the contour of the said part. Now, when in the operation of the system of which the present in- 55 vention forms part, air is exhausted from the casing, the atmospheric pressure on the portion of the elastic sleeve, exteriorly of the same, will effect an air-tight closure around the part of the body with which said sleeve engages, and when compressed air is 60 admitted to the casing, its pressure on the portion of the sleeve within the casing will produce a similar effect, it being understood that the shutters 22 prevent displacement of the sleeve by limiting the deflection of their 65 flanges by means of which it is secured to

the sections of which the holding-element of the closing appliance is composed.

In the casing shown in Fig. 1, the shutters at the inner sides of the closing appliances around the arm openings have been omitted 70 as their proximity to the arm pits would hinder their adjustment.

The upper half of the casing shown in Figs. 1, 2 and 5 is provided with a hand-hole 35 normally closed by a cover 36 which is held in place by clamps 37 similar to those used for securing the two halves of the casing. The member 36 has a central opening which is closed by a glass plate 38 beneath which is secured a gage 39 adapted to indicate the degree of air pressure within the casing. A nipple 40 on the lower half of the casing is provided for the attachment of a tube or pipe connected with an air pump by the use of which air is exhausted from 85 the casing or air under pressure is supplied to the same. When the casing is used in connection with a flexible garment such as is shown at 41 in Fig. 6, an air-tight connection between the two elements is effected by 90 securing the open end of the garment around one of the openings of the casing after the shutters and the elastic body-engaging members of the corresponding closing-appliance have been detached. The connection of the garment with the casing may be effected either by clamping the edge of the garment around its opening between the members 10 and 13 of the sections 9 or by providing the garment with a flange which 95 in form corresponds to the combined inner members 13 of the section, and which when placed within the rim of the body members of the sections, is clamped in position by the springs 17.

100 In the form of my invention shown in Fig. 3, the casing is tubular and provided at its opposite ends with closing devices similar to those hereinbefore described.

In the construction illustrated in Fig. 4, 110 the casing is made in the form of a helmet likewise made of two parts and provided at its lower end with closing means of the character described, and in its front with a glass covered opening through which the 115 features of a patient around whose head the casing is applied, may be observed.

After the casing shown in Fig. 1 is applied around the thorax of a body and the openings through which the adjoining parts 120 of the body extend are closed in the manner hereinabove described, air may be exhausted from the casing or air under pressure supplied thereto by the action of a pump connected with the nipple 40. This form of 125 my invention is particularly adapted for the treatment of consumption of the lungs, pneumonia or other pulmonary diseases, and when the rubber garment 41 is used in connection with the casing, the treat- 130

ment is aided by inducing a flow of blood to the lungs to relieve the heart and feed diseased tissues, each time a partial vacuum is produced within the casing, and the therewith communicating garment is in consequence forced to hug the lower portions of the body by pressure of the atmosphere.

The casing illustrated in Fig. 3, is adapted to be used on the limbs of a patient for the principal purpose of producing artificial hyperemia in case of mal-nutrition or anemia, and the helmet shown in Fig. 4 is particularly adapted for the purpose of forcing air directly into the lungs and drawing it out again to artificially produce respiration in case of asphyxiation.

Having thus described my invention I desire it understood that my improved casing may be made in forms other than those shown, to be used in the therapeutic treatment of different parts of the body, by the method hereinabove described; and that the construction of the means for closing the spaces between the parts of the body adjoining the portion to be treated, and the edges of the openings through which these parts extend, may be varied within the spirit of my invention as defined in the following claims:

1. A casing for producing an air-tight chamber over or around a portion of the human body, composed of two parts and having an orifice for the exhaust or admission of air and at the junction of said parts, an opening to receive a part of the body adjoining said portion, means for securing the parts of the casing in air-tight connection, and means for effecting an air-tight closure of the space between the edge of said opening and a part of the body extending through the same, composed of co-operative complementary sections which are applied around the opening to the two parts of the casing.

2. A casing for producing an air-tight chamber around a portion of the human body, having passages for parts of the body adjoining said portion and an orifice for the exhaust or admission of air and an opening, separate from said passages, to afford access to a portion of the body within the casing; a cover for closing said opening, and means to removably secure said cover in air-tight connection with the casing.

3. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a

flexible sleeve having intermediate of its ends, a circumferential flange which holds the sleeve within the opening and closes the surrounding space of the same, whereby the sleeve extends partially within the casing and partially exteriorly of the same.

4. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve having intermediate of its ends, a circumferential flange which holds the sleeve within the opening and closes the surrounding space of the same, whereby the sleeve extends partially within the casing and partially exteriorly of the same, and adjustable means for compelling said sleeve to engage and conform with a part of the body it encircles.

5. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve having intermediate of its ends, a circumferential, flexible flange which holds the sleeve within the opening and closes the surrounding space of the same, whereby the sleeve extends partially within the casing and partially exteriorly of the same, the said flange being formed to provide an air-chamber at the line along which it joins the sleeve for the purpose specified.

6. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve having intermediate of its ends a circumferential, flexible flange which holds the sleeve within the opening and closes the surrounding space of the same, whereby the sleeve extends partially within the casing and partially exteriorly of the same, adjustable means for compelling the sleeve to engage and conform with a part of a body it encircles, and means for preventing displacement of said sleeve by limiting lateral deflection of its flange.

7. A casing for producing an air-tight chamber over or around a portion of the human body, having an orifice for the ex-

- haust or admission of air, and an opening to receive a part of the body adjoining said portion, and means for effecting an air-tight closure of the space between the edge of said opening and the part of the body extending through the same, including a flexible sleeve having intermediate of its ends, a circumferential, flexible flange which holds the sleeve within the opening and closes the surrounding space of the same, whereby the sleeve extends partially within the casing and partially exteriorly of the same, and means for preventing displacement of said sleeve by limiting lateral deflection of its flange. 5

10 8. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve disposed within the opening and having a circumferential flange, and a holding element secured to the casing and adapted to secure the sleeve by engagement with its flange. 15

20 9. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve disposed within the opening and having a circumferential flange, a holding element secured to the casing and adapted to secure the sleeve by engagement with its flange, push-bars slideable on said element to engage the outer surface of the sleeve for compelling it to engage and conform with a part of the body it encircles, and shutter blades on said holding element, adjacent the sides of the flange for limiting lateral deflection of the same. 25

30 10. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve disposed within the opening and having a circumferential flange, a holding element secured to the casing and adapted to secure the sleeve by engagement with its flange, and adjustable means on said element, for compelling said sleeve to engage and conform with a part of the body it encircles. 35

40 11. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve disposed within the opening and having a circumferential flange, a holding element secured to the casing and adapted to secure the sleeve by engagement with its flange, and push bars slideable on said element to engage the outer surface of the sleeve for compelling it to engage and conform with a part of the body it encircles. 45

50 12. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve disposed within the opening and having a circumferential flange, a holding element secured to the casing and adapted to secure the sleeve by engagement with its flange, push-bars slideable on said element to engage the outer surface of the sleeve for compelling it to engage and conform with a part of the body it encircles, and shutter blades on said holding element, adjacent the sides of the flange for limiting lateral deflection of the same. 55

60 13. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve disposed within the opening and having a circumferential flange, a holding element secured to the casing and adapted to secure the sleeve by engagement with its flange, push-bars slideable on said element to engage the outer surface of the sleeve for compelling it to engage and conform with a part of the body it encircles, and shutter blades carried on said push bars adjacent the sides of the flange for limiting lateral deflection of the same. 65

65 14. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve disposed within the opening and having a

circumferential flange, a holding element secured to the casing and adapted to secure the sleeve by engagement with its flange, push bars slidable on said element, to engage the outer surface of the sleeve for compelling it to engage and conform with a part of the body it encircles, and shutter blades pivotally mounted on said push bars, and extending adjacent the sides of the flange 10 for limiting lateral deflection of the same.

15. A casing for producing an air-tight chamber over or around a portion of the human body, having an orifice for the exhaust or admission of air, and an opening 15 to receive a part of the body adjoining said portion, and means for effecting an air-tight closure of the space between the edge of said opening and the part of the body extending through the same, including a flexible sleeve 20 disposed within the opening and having a circumferential flange, a holding element secured to the casing and adapted to secure the sleeve by engagement with its flange, push bars slidable on said element to engage 25 the outer surface of the sleeve for compelling it to engage and conform with a part of the body it encircles, and spring-pressed shutter-blades pivotally mounted on said push-bars and extending adjacent the sides of the 30 flange for limiting lateral deflection of the same.

16. A casing for producing an air-tight chamber over or around a portion of the human body, having an orifice for the exhaust or admission of air, and an opening 35 to receive a part of the body adjoining said portion, and means for effecting an air-tight closure of the space between the edge of said opening and the part of the body extending 40 through the same, including a flexible sleeve disposed within the opening and having a circumferential flange, a holding element secured to the casing and adapted to secure the sleeve by engagement with its flange, and adjustable means on said element, adapted to 45 engage the sleeve for compelling it to engage and conform with a part of the body it encircles, the said sleeve having outwardly projecting wings for its manual adjustment.

50 17. A casing for producing an air-tight chamber over or around a portion of the human body, having an orifice for the exhaust or admission of air, and an opening 55 to receive a part of the body adjoining said portion, and means for effecting an air-tight closure of the space between the edge of said opening and the part of the body extending through the same, including a flexible sleeve disposed within the opening and composed 60 of two halves provided with the complementary portions of a circumferential flange of the sleeve and with outwardly projecting portions for the manual adjustment of the sleeve, a holding element secured to the 65 casing and adapted to secure the halves of

the sleeve by engagement with their respective flange-portions, and adjustable means on said element adapted to engage the exterior surface of the sleeve for compelling it to engage and conform with a part of the body it encircles.

18. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve disposed within the opening and composed of two halves provided with the complementary portions of a circumferential flange of the sleeve, and a holding element secured to the casing and composed of two complementary sections, adapted to secure the sleeve by engagement with the flange-portions of its halves.

19. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve disposed within the opening and composed of two halves provided with the complementary portions of a circumferential flange of the sleeve, and a holding element secured to the casing and composed of two complementary sections, adapted to secure the sleeve by engagement with the flange-portions of its halves, and each composed of two members relatively disposed to receive one of said flange portions between them, and adjustable means for clamping said members together.

20. A casing for producing an air-tight chamber over or around a portion of the human body, having an orifice for the exhaust or admission of air, and an opening to receive a part of the body adjoining said portion, and means for effecting an air-tight closure of the space between the edge of said opening and the part of the body extending through the same, including a flexible sleeve disposed within the opening and having a circumferential flange, a holding element secured to the casing and composed of two complementary sections, adapted to secure the sleeve by engagement with the respective portions of the flange, and push bars slidable on said sections to engage the sleeve for compelling it to engage and conform with a part of the body it encircles.

21. A casing for producing an air-tight chamber over or around a portion of the human body, having an orifice for the ex-

haust or admission of air, and an opening to receive a part of the body adjoining said portion, and means for effecting an air-tight closure of the space between the edge 5 of said opening and the part of the body extending through the same, including a flexible sleeve disposed within the opening and having a circumferential flange, a holding element secured to the casing and composed 10 of two complementary sections, adapted to secure the sleeve by engagement with the respective portions of its flange, and push bars slidable on said sections to engage the sleeve at opposite sides of its flange for 15 compelling it to engage and conform with a part of the body it encircles.

22. A casing for producing an air-tight chamber over or around a portion of the human body, having an orifice for the exhaust or admission of air, and an opening 20 to receive a part of the body adjoining said portion, and means for effecting an air-tight closure of the space between the edge of said opening and the part of the body 25 extending through the same, including a flexible sleeve disposed within the opening and having a circumferential flange, a holding element secured to the casing and consisting of complementary halves each composed 30 of two members relatively disposed to receive corresponding portions of the flange between them, and means for clamping said members together, and push bars 35 slidably mounted on the members of said sections, to engage the sleeve for compell-

ing it to engage and conform with a part of the body it encircles.

23. A casing for producing an air-tight chamber over or around a portion of the human body, having an orifice for the exhaust or admission of air, and an opening 40 to receive a part of the body adjoining said portion, and means for effecting an air-tight closure of the space between the edge of said opening and the part of the body 45 extending through the same, including a flexible sleeve held within said opening and having means for its adjustment to engage a part of the body it encircles.

24. A casing for producing an air-tight 50 chamber over or around a portion of the human body, having an orifice for the exhaust or admission of air, and an opening to receive a part of the body adjoining said portion, and means for effecting an air-tight closure of the space between the edge 55 of said opening and the part of the body extending through the same, including a flexible sleeve held within said opening and having means for its adjustment to engage 60 a part of the body it encircles, and adjustable means for compelling the sleeve to conform with the contour of said part.

In testimony whereof I have affixed my signature in presence of two witnesses.

CHARLES E. H. ARMBRUSTER.
